UNITED STATES PATENT OFFICE

JOHN RALPH HOGE AND LEONARD D. SOUBIER, OF TOLEDO, OHIO, ASSIGNEES TO
OWENS-ILLINOIS GLASS COMPANY, OF TOLEDO, OHIO, A CORPORATION OF OHIO

MECHANISM FOR HANDLING BOTTLES AND JARS

Application filed June 26, 1932. Serial No. 373,807.

The present invention relates to improvements in mechanism for handling bottles and jars and more particularly means for removing them from the molds of a forming machine and transferring them to the interior of a tempering oven or annealing leer.

An object is to provide automatic means for removing finished articles of glassware from the forming molds and supporting them against sagging or elongation during transfer to positions within the leer. To this end the invention includes a device which engages the upper portions of the articles of glassware and after removing the latter from the molds, projects a bottom plate into position beneath and in supporting contact with the articles of glassware, said device then carrying the articles to positions within the leer.

20 A further object is to provide automatic means for removing articles of glassware from forming molds and placing them spaced apart in rows in an annealing leer, said means supporting the glassware against sagging during transfer from the machine to the leer.

Other objects will be apparent hereinafter.

In the drawings:

30 Fig. 1 is a plan view more or less diagrammatically illustrating the invention and the manner in which it operates.

Fig. 2 is a plan view showing two positions of the takeout and transfer device, the position at the left illustrating the first step in which the neck portion only of the bottle is engaged by the device, and the position at the right showing the device after the bottom supporting arm or plate is operatively positioned.

Fig. 3 is a sectional view with parts in elevation taken substantially along the line III-III of Fig. 2.

45 Fig. 4 is a sectional view taken along the line IV-IV of Fig. 2.

Fig. 5 is a fragmentary side elevation looking toward one end of the device, as indicated by the arrow shown on Fig. 1.

50 Fig. 6 is a fragmentary sectional elevation showing the bottom supporting plate

and means for locking it in its retracted or inoperative position.

Fig. 7 is a view similar to Fig. 6 showing the bottom supporting plate projected.

Fig. 8 is a transverse sectional view taken substantially along the line VIII-VIII of Fig. 7.

Fig. 9 is a sectional view taken substantially along the line IX-IX of Fig. 3.

Fig. 10 is a detail perspective view of a portion of the takeout and transfer device.

Fig. 11 shows the transfer device supporting a bottle within the annealing leer.

Fig. 12 shows the transfer device in the leer, the bottom supporting plate having been removed from beneath the bottle so that the latter rests upon the leer conveyor.

The preferred embodiment of our invention is illustrated in conjunction with a rotary type bottle blowing machine 15 including portable finishing molds 16 each comprising a pair of mold sections 17 pivoted to a vertical hinge pin 18 and movable toward and from each other at regular time intervals. A bottom plate 19 cooperates with each finishing mold in final shaping of the articles of glassware and as will be apparent presently may support the articles for a short period of time after the finishing mold opens so that a combined takeout and transfer device may be positively engaged with the upper portions of said articles.

80 A glassware annealing leer 20 may be arranged with its receiving end adjacent the blowing machine 15. This leer includes a leer conveyor 21 extending lengthwise of the leer tunnel to convey glassware through the latter. Transversely aligned openings 22 are formed in the side walls of the leer, permitting movement of the transfer devices 90 over the leer conveyor.

85 Means to remove the finished articles of glassware from the finishing molds 16 and transfer them to the leer conveyor 21 includes a series of takeout and transfer devices whose movements are synchronized with those of the finishing molds so that when a finishing mold reaches the ware ejecting station one of the takeout and transfer devices immediately moves into position to 100

engage the neck of an article while the latter is supported on the bottom plate. These transfer devices (Fig. 1) are supported on an endless chain 23 running over sprockets 24 and through the openings 22 in the side walls of the leer 20. This chain 23 is subject to continuous movement in order to bring the takeout and transfer devices in succession to positions for removing glass articles from the finishing molds and placing them in rows extending across the leer conveyor 21.

Each takeout and transfer device first grips the upper end or neck of a bottle while the latter is supported on a finishing mold 15 bottom plate 19 and a moment later replaces said bottom plate with a supporting arm 28 which prevents the bottle from sagging or becoming otherwise distorted. Each of these devices (Figs. 3 to 10 inclusive) comprises 20 a horizontal base 25 carrying at one end an extensible upright 26 or standard, the latter connected through an arm 27 (Fig. 4) to the sprocket chain 23. The upright 26 includes 25 two bars bolted together and capable of lengthwise adjustment to vary the spaced relation between a bottom supporting arm 28 and neck gripping device 29 or jaws at the upper end of the upright.

The neck engaging device 29 (Figs. 3, 4, 30 9, 11 and 12) mounted upon the upper end of the upright 26 includes a stationary jaw 30 and movable jaw 31, the latter pivoted to a horizontal hinge pin 32 at the outer end of a horizontal arm 33 which is formed on the 35 upper section of the upright. The movable jaw 31 is formed with a notch 34 in which the neck of the bottle B is arranged during the takeout and transfer operation. This movable jaw 31 is normally held in a plane 40 above the upper ends of the articles of glassware as shown in Figs. 11 and 12. This positioning of the jaw 31 is obtained by an expansion spring 35 which encircles a push rod 36 extending through a horizontal opening 45 in the upright and connected through a link 37 to an arm 38 formed on the jaw. The other end of this push rod 36 carries a cam roll 39 which engages a cam 40 (Figs. 4 and 1) during movement between the ware ejecting station E and the point at which the devices enter the annealing leer.

The bottom supporting arm 28 (Figs. 3, 4, and 6 to 10 inclusive) which supportingly contacts with the bottoms of the articles, is 55 arranged in a horizontal guideway 45 formed in the base 25, said arm being secured to a slide block 46 in a slideway 47. The slide block 46 is adapted for reciprocation in the slideway 47 in order to alternately project and 60 retract the bottom supporting arm 28. A pair of coil springs 48 (Figs. 6 and 10) may be employed to move the slide block toward the upright 26 (Fig. 7) and thereby position the arm 28 beneath the bottle or similar article 65 of glassware. Movement of the block in the

opposite direction is obtained by a cam roll 49 carried by the slide block 46 and adapted to be engaged by a trip device at regular time intervals as will be described presently. The slide block 46 and arm 70 28 may be locked in their retracted position. This is obtained by arranging a spring pressed detent 50 in a recess formed in the lower side of the slide block 46 (Figs. 6, 7 and 8). When the slide block is fully retracted (Fig. 6) the detent 50 is vertically aligned with and positioned in an upwardly opening recess 51 in the base 25 so that accidental relative movement between the arm and base is avoided. Release of the slide 80 block and arm for movement under influence of the coil springs 48 is obtained by upward movement of a push rod 52 whose lower end projects below the base 25 and is adapted to engage a stationary cam 53 (Figs. 1, 2, 7 and 85 8) arranged a short distance beyond the station E at which the jaws engage the articles being removed from the machine.

The takeout and transfer devices and supporting chain 23 therefor are held against 90 sagging or tilting by upper and lower rails 55 and 56 respectively. A grooved roller 57 carried by the upright 26 rides upon the upper rail 55 and prevents downward movement or sagging of the chain and devices carried 95 thereby. A grooved roller 58 carried by the base 25 rides on the rail 56 and prevents tilting of the takeout and transfer devices. Thus these devices are securely held against assuming abnormal positions which might result in 100 distortion or dropping of the articles of glassware removed from the forming machine.

The takeout and transfer devices move in succession transversely of the annealing leer through the opening 22 (Figs. 1, 11 and 12) 105 preparatory to placing the articles of glassware upright upon and in transverse rows across the leer conveyor 21. Just before one of the transfer devices enters the leer, the jaw 31 (Figs. 3, 11 and 12) releases the neck 110 portion of the bottle or other article being transferred so that the latter is entirely supported upon the arm 28 as shown in Figs. 7 and 11. This operation is due to termination 115 of the cam 40 at a point adjacent the entrance opening 22. Immediately after the transfer device moves beyond the end of the cam 40, the spring 35 swings the jaw 31 to the position shown in Figs. 11 and 12.

The transfer devices are actuated one at a 120 time while moving over the leer conveyor 21 to set the articles upright and in spaced relation upon the leer conveyor. This is obtained by removing the supporting plate 28 from its position beneath the article of glassware. The structure by which this is accomplished comprises a cam 60 arranged within the leer tunnel and adapted to be reciprocated transversely thereof. This cam (Figs. 1, 11 and 12) 125 engages the cam rolls 49 one at a time and 130

thereby moves the bottom supporting plate or arm 28 from the position shown in Fig. 7 to that shown in Fig. 6. In the latter position the detent 50 automatically locks the arm against premature outward movement.

The cam 60 (Figs. 1, 11 and 12) is mounted on the outer end of an arm 61 suitably connected to a threaded shaft 62, the latter journaled in bearings 63 at opposite sides of the leer and continuously rotated by means (not shown) operating through a sprocket chain 64 and sprocket 65. Movement of the forming machine, takeout and transfer devices, and the cam 60 are so synchronized that said devices arrive at the ware ejecting station at proper time intervals and the cam 60 effects release of the articles from said devices in a fashion to arrange the articles spaced apart and in transverse rows across the conveyor 21.

In operation, the takeout and transfer devices are continuously moved in the direction indicated by the arrows in Fig. 1 so that they are brought in succession to the ware ejecting station E. When one of the devices arrives at the ware ejecting station, a finishing mold 16 opens leaving an article of glassware supported on the bottom plate 19. The cam 40 now engages the cam roll 39 and thereby causes movement of the jaw 31 (Figs. 3 and 9) into engagement with the neck of the bottle or other article of glassware. This neck gripping operation may take place prior to opening of the finishing mold, if desired. Continued movement of the forming machine 15 causes removal of the bottom plate 19 from beneath the bottle B and leaves the latter suspended from the neck gripping device 29. Almost immediately the bottom supporting arm 28 is projected to the position shown in Fig. 4 wherein it contacts with the bottom of the bottle. Such projection of this arm 28 is obtained by upward movement of the detent 50 which permits the coil spring 48 to project said arm 28 as shown in Figs. 4 and 7. Thus the bottle is held against sagging. Just before the device enters the leer, the movable jaw 31 is swung upwardly to the position shown in Figs. 11 and 12 so that the bottle is free to move in the direction of travel of and with the leer conveyor 21. At a predetermined point in its travel across the leer, the bottom supporting plate 28 is retracted so that a bottle stands upright upon the leer conveyor 21. As previously pointed out, retraction of the arm or plate 28 is obtained by means of the cam 60 which moves back and forth across the leer and during movement in one direction successively engages the cam rolls 49 on the takeout and transfer devices and thereby causes positioning of the arms as shown in Figs. 6 and 12. In this manner the articles of glassware are placed upright and in transverse rows upon the leer conveyor.

Modifications may be resorted to within the spirit and scope of the appended claims.

What we claim is:

1. In combination, a series of article forming molds movable in succession past a mold opening station, a series of devices movable past said station in timed relation to movement of said molds, each device including a gripper adapted to engage the upper ends of the articles, means movable into and out of position for supporting engagement with the bottoms of said articles, and means for actuating the devices. 70

2. In combination, a series of article forming molds movable in succession past a mold opening station, a series of takeout and transfer devices movable in succession past said station in timed relation with movement of said molds, each device including means to grip the upper portion of an article at said station, means movable into position to support the lower portion of the article, and means spaced from said station for removing the articles from said devices. 80

3. In combination, a series of partible molds adapted to form articles of glassware, said molds movable in succession past a mold opening station, a series of takeout and transfer devices movable in succession past said station, each of said devices including separate means to engage the neck portions and bottoms of the articles of glassware, and means to successively actuate the neck and bottom supporting means in releasing articles from the combined takeout and transfer devices. 95

4. In combination, a series of article forming molds movable in succession past a mold opening station, a horizontally extending conveyor spaced from said station, means to transfer articles from the molds to the conveyor comprising a series of takeout and transfer devices movable in succession past said station and over said conveyor, said devices each comprising cam actuated means to grip the upper portions of the articles, cam actuated means to support the lower portions of the articles, and means associated with the conveyor for releasing the articles from the devices one at a time and setting them upright upon the conveyor. 105

5. In combination, a series of article forming molds movable in succession past a mold opening station, a horizontally extending conveyor spaced from said station, means to transfer articles from the molds to the conveyor comprising a series of takeout and transfer devices movable in succession past said station and over said conveyor, said devices each comprising cam actuated means to grip the upper portions of the articles, cam actuated means to support the lower portions of the articles, a cam arranged for movement over the conveyor, and means to impart a reciprocating movement to the cam, said 110

120

125

130

cam operating during travel in one direction to cause removal of articles from the takeout and transfer devices and positioning of the articles upon the conveyor.

- 5 6. In combination, an article takeout and transfer device comprising a pair of jaws adapted to grip the upper portion of an article, and an article supporting arm arranged below said jaws and adapted at times to engage the bottom of the article, said arm adapted to be reciprocated between operative and inoperative positions.
- 10 7. In combination, an article takeout and transfer device comprising a pair of jaws adapted to grip the upper portion of an article, a supporting arm arranged below said pair of jaws and adapted at times to engage the bottom of the article, said arm adapted to be reciprocated between operative and inoperative positions, and extensible means connecting said jaws and arm.

- 15 8. In combination, an article takeout and transfer device comprising a pair of jaws adapted to grip the upper portion of an article, a supporting arm arranged below said pair of jaws and adapted at times to engage the bottom of the article, said arm adapted to be reciprocated between operative and inoperative positions, yielding means normally holding said jaws in an inoperative position, and yielding means tending to move said arm to an operative position.

- 20 9. In combination, an article takeout and transfer device comprising a pair of jaws adapted to grip the upper portions of articles to be transferred, a supporting arm arranged below said jaws to engage the bottoms of said articles, said arm adapted for reciprocation between operative and inoperative positions, a spring pressed detent to releasably hold said arm in its inoperative position, and cam controlled means for releasing the arm from the influence of said detent.

- 25 10. In combination, an article takeout and transfer device comprising a pair of jaws adapted to grip the upper portions of articles to be transferred, a supporting arm arranged below said jaws to engage the bottoms of said articles, said arm adapted for reciprocation between operative and inoperative positions, a spring pressed detent to secure said arm in its inoperative position, cam controlled means for releasing the arm from the influence of said detent, and means to change the vertical spaced relation between said jaws and arm.

- 30 11. In combination, a series of article forming molds movable in succession past a mold opening station, a horizontally extending conveyor spaced from said station, means to transfer articles from the molds to the conveyor comprising a series of devices movable in a closed path extending over the conveyor and past said station, each of said devices comprising means to grip the upper

35 portions of the articles, means movable into supporting contact with the bottoms of the articles to support the latter against elongation, and means spaced from said station whereby the articles may be released from the devices one at a time and set upon the conveyor.

40 12. In combination, a series of article forming molds movable in succession past a mold opening station, a horizontally extending conveyor spaced from said station, means to transfer articles from the molds to the conveyor comprising a series of takeout and transfer devices movable in succession past said station and over the conveyor, said devices each comprising means to grip the upper portions of the articles, cam actuated means movable into supporting contact with the bottoms of the articles to support the latter against elongation, and cam means associated with the conveyor for releasing articles from the devices one at a time and setting them upon the conveyor.

45 13. In combination a series of portable article forming molds movable in succession past an article discharging station, bottom plates individual to the molds, said molds adapted to open at the station leaving articles supported on the bottom plates, a series of combined takeout and transfer devices movable past said station in timed relation to movement of said molds, each device including a gripper adapted to engage an upper portion of the articles, a supporting arm adapted to engage the bottom of the articles, means causing projection of the gripper at the discharging station into engagement with an article to remove the latter from the mold and bottom plates, and means for then projecting the supporting arm to an operative position beneath said article.

50 Signed at Toledo, in the county of Lucas and State of Ohio, this 20th day of June, 1929.
